UNITED STATES PATENT OFFICE.

JOHN S. BRENNAN, OF MILWAUKEE, WISCONSIN.

VALVE FOR HEATING SYSTEMS.

1,158,893.

Specification of Letters Patent.

Patented Nov. 2, 1915.

Application filed April 27, 1914. Serial No. 834,685.

To all whom it may concern:

Be it known that I, JOHN S. BRENNAN, a citizen of the United States, and resident of Milwaukee, in the county of Milwaukee and 5 State of Wisconsin, have invented certain new and useful Improvements in Valves for Heating Systems; and I do hereby declare that the following is a full, clear, and exact description thereof.

10 My invention has for its object to provide an automatic thermostatically controlled valve that is attached to the return end of each radiator, the said valves being also in communication with a vacuum controlled return pipe system. By this peculiarly constructed valve each radiator of the system is freed from air and water of condensation, while, at the same time, the said valve operates to close the return end of 15 the radiator automatically when said radiator has reached a predetermined high temperature due to the introduction of vapor or steam therein in the desired quantity. Closing of the valve thus prevents the escape of 20 steam or vapor, which valve prior to its closing, permits the escape of air and water coincident to the introduction of the heating medium. Thus it will be seen that the radiators or heat units of the entire system are 25 effectually controlled to produce their maximum heating efficiency; to provide a thermostatic diaphragm in connection with the automatic valve, whereby said valve is rendered sensitive to heat and will thus close or 30 open under variations of temperature; to provide means for adjusting the diaphragm-controlled valve-member with relation to its seat, whereby the sensitiveness of the valve 35 is controlled; to provide spring-controlled 40 means in opposition to the expansive force of the diaphragm, which spring-controlled means also serves as a strainer to prevent foreign substances from clogging said valve; to provide means for eliminating the noise 45 or rattle in the automatically actuated valve.

With the above and other minor objects in view the invention consists in certain peculiarities of construction and combination of parts as set forth hereinafter with reference to the accompanying drawings and subsequently claimed.

In the drawings Figure 1, an enlarged detailed sectional view of an automatic valve embodying the features of my invention, the 55 section being indicated by line 2—2 of Fig. 2, which valve is the primary element in the

system for effecting the desired results; Fig. 2, a plan view of the same with parts broken away and parts in section, and Fig. 3, an inverted detailed plan view of the valve-cap. 60

Referring by characters to the drawings with special reference to Figs. 1 to 3 inclusive, the casing of the automatic valve B is provided with a receiving throat 14, which throat is restricted by a trap-plate 14' that 65 extends to a point adjacent to the lower wall of said throat or bottom of the valve chamber 15. The valve chamber is provided with a centrally disposed threaded discharge mouth 16, which mouth communicates with 70 a return pipe of the system. The discharge mouth has fitted therein a valve-seat plug 17, which plug is in threaded union with the mouth and is thus arranged to be adjusted up or down relative to a valve member 75 18. The valve member 18, in this instance, comprises an offset hollow nib of a hollow diaphragm 20, which diaphragm is in the form of a disk that is filled with suitable liquid, the same being highly sensitive 80 to variations in temperature, whereby the diaphragm is expanded or contracted under the influence of said liquid. In order to add durability to the diaphragm, whereby it is prevented from collapsing under strain, 85 I provide a metallic spider 21, which spider is fitted therein prior to the diaphragm being completed, a hub 21' of the spider being extended into the offset valve member 18 to thus support the walls in all directions. 90 The working face of the valve-member or nib 18, as shown, is thus rendered slightly flexible, whereby perfect seating of the valve is insured.

In order to hold the valve-member normally away from its seat, whereby the discharge mouth is, under ordinary conditions, open, I provide a coiled spring 22, which coiled spring surrounds the valve-plug and hollow nib constituting the valve member, 100 the ends of said spring being seated against the bottom face of the valve chamber 15 and opposite wall of the diaphragm. Thus it will be observed that the diaphragm is forced upward under spring pressure and, 105 owing to the fact, as shown, that the coiled spring is quite closely wound, the said spring serves as a screen to protect the discharge mouth from being clogged by foreign matter that may pass into the valve chamber. 110 The valve casing is provided with a closure-cap 23, which cap is formed with a series of

concentric circular ribs 24 that are adapted to engage the upper wall of the diaphragm and against which ribs the diaphragm is forced in opposition to the coiled spring 22. 5 The circular ribs are provided with series of radial notches 24', as best shown in Fig. 3, whereby the entire surface of the diaphragm is exposed to the surrounding temperature of the valve-chamber, to thus render the dia- 10 phragm extremely sensitive to variations in temperature, whereby it will act quickly in performing its functions.

From the foregoing description it will be observed that, by the adjustment of the 15 valve seat with relation to the valve member, closure of the valve due to expansion may be predeterminedly regulated, while at the same time such adjustment does not vary the tension of the valve spring. Hence the 20 unseating tension of the same remains constant irrespective of the relative positions of said valve member and its seat.

Referring to the thermal-controlled automatic valve shown in Fig. 1, it is obvious 25 that, owing to the arrangement of trap-plate 14', should a small quantity of water settle in the valve-chamber, the ordinary rattle or noise incidental to suction produced upon the return pipe, will be eliminated 30 for the reason that the water within the valve-chamber will seal the restricted throat opening to prevent gurgle.

From the foregoing description it is apparent that after the radiators have been 35 either partly or wholly filled with vapor or steam, the heat entering the valve-chamber 15 of the automatic valve, will cause the diaphragm to expand and thus close communication between the radiator and return 40 pipe system. Hence there is no liability under, ordinary working conditions, of

vapor entering the return pipe system, which vapor, if permitted to enter said return pipe system, would cut off the series of radiators and cause a back pressure whereby 45 their heating efficiency would be impaired. This automatic valve also prevents the escape of vapor to the atmosphere, whereby economy in the system is effected.

I claim:

1. A thermostatically controlled valve for heating systems comprising a cap-closing casing having a receiving throat and a discharge mouth constituting a valve seat, a diaphragm fitted into the casing having one of its walls extended to form a centrally disposed offset nib provided with a flat working face adapted to serve as a closure for the valve seat, a reinforcing spider in the diaphragm having a hub extending into the nib and a valve unseating spring surrounding the nib interposed between the face of the diaphragm and about the valve seat.

2. A thermostatically controlled valve, 65 comprising a double-walled diaphragm, the walls being spaced apart to form a fluid chamber, one wall of which is distended to constitute a hollow nib in communication with the chamber, one face of the nib being 70 flattened to form a flexible valve closure, and reinforcing means in the chamber and nib.

In testimony that I claim the foregoing I have hereunto set my hand at Milwaukee in the county of Milwaukee and State of Wisconsin in the presence of two witnesses.

JOHN S. BRENNAN.
